DESIGN FOR A BAR BOTTLE OR ARTICLE OF
SIMILAR NATURE

T. Clarence Heisey, Newark, N. J., assignor to
A. H. Heisey & Company, Newark, Ohio, a corporation of Ohio

Application April 29, 1941, Serial No. 100,683

Term of patent 3½ years

To all whom it may concern:

Be it known that I, T. Clarence Heisey, a citizen of the United States of America, residing at Newark, in the county of Licking and State of Ohio, have invented a new, original, and ornamental Design for a Bar Bottle or Article of Similar Nature, of which the following is the specification, reference being had to the accompanying drawing, forming a part thereof.

or article of similar nature, showing my new design.

I claim:

The ornamental design for a bar bottle or article of similar nature, substantially as shown.

T. CLARENCE HEISEY.
